US00D851406S

(12) **United States Design Patent** (10) **Patent No.:** **US D851,406 S**
Schiffer (45) **Date of Patent:** **** Jun. 18, 2019**

(54) **TOOTHBRUSH**

(71) Applicant: **M+C SCHIFFER GmbH**,
Neustadt/Wied (DE)

(72) Inventor: **Kuros Schiffer**, Neudstadt-Wied (DE)

(73) Assignee: **M+C SCHIFFER GmbH**,
Neustadt/wied (DE)

(**) Term: **15 Years**

(21) Appl. No.: **35/502,429**

(22) Filed: **Aug. 11, 2016**

(80) **Hague Agreement Data**

Int. Filing Date: **Aug. 11, 2016**

Int. Reg. No.: **DM/094498**

Int. Reg. Date: **Aug. 11, 2016**

Int. Reg. Pub. Date: **Feb. 10, 2017**
